UNITED STATES PATENT OFFICE.

ARTHUR W. MATHEWSON, OF FALL RIVER, MASSACHUSETTS.

THREAD-GUIDING AND TENSION-REGULATING DEVICE FOR SPOOLING AND WINDING MACHINES.

SPECIFICATION forming part of Letters Patent No. 369,868, dated September 13, 1887.

Application filed January 23, 1886. Serial No. 189,715. (No model.)

To all whom it may concern:

Be it known that I, ARTHUR W. MATHEWSON, of the city of Fall River, county of Bristol, and State of Massachusetts, have invented certain new and useful Improvements in Thread-Guiding and Tension-Regulating Devices for Spooling and Winding Machines, of which the following is a full, clear, and exact description, reference being had to the accompanying drawings, forming part of this specification.

My invention relates to the class of spooling and winding machines which wind the cotton thread onto rotating spools from bobbins or cops mounted upon spindles.

In the ordinary spooling and winding machines the great distance between the delivery end of the bobbin and the eye of its thread-guide allows the thread to widely balloon out and form itself into loops. This looping and beating about causes such a great air-drag as to seriously injure the uniformity of the filament of thread by the tendency to shake loose the fibers from the filament, making it rough and inferior for weaving purposes. Again, because of this wide adjustment between the end of the bobbin and the eye of its thread-guide the spooling and winding process has necessarily to be accomplished at a low rate of speed. Otherwise high speed would cause such exaggerated ballooning and whipping about of the thread as to be ruinous to it.

The objects of my invention are to provide improvements in this class of machines, whereby in spooling and winding thread high speed can be obtained without the usual resultant injury to the thread, which is delivered to the spool rapidly and in a very perfect condition by my device.

To the above purposes my invention consists in the very close relative adjustment of the delivery end of the bobbin and of the co-operating thread guide, and in other sub-combinations, all hereinafter fully described and claimed.

In the accompanying drawings, Figure 1 represents a front elevation of my improvements with the bobbin mounted upon its spindle. Fig. 2 represents a side elevation of Fig. 1, the broken lines representing the clamp, with its thread-guide and friction roll tilted back into abnormal position. Fig. 3 represents

a side elevation of another form of my device, part shown in section. Fig. 4 represents a top plan view of my devices with the friction-roll removed. Fig. 5 represents a sectional view on line 5-5, Fig. 2, the friction-roll being removed and the standard broken off. 55

In the said drawings like numbers designate like parts throughout.

In the illustrations I have shown only the immediate parts of the machine which have to do with my device, so the spool and its adjuncts are not shown. The spindle-step 6 is located upon the base of the supporting-standard 7, and carries the dead-spindle upon which the ordinary bobbin, 8, is mounted. The standard 7 is a tapering upright piece having four lateral ribs, though it may be of any shape, and at its head broadens out and carries two ears, 9, which are perforated to receive the pivot-bar 10, upon which sets and turns the lower plate, 11, of the thread-guide clamp. This plate 11 is quite thick and is suitably formed to have tilting play upon its pivot equal to the difference between its normal and abnormal positions. (Shown in Fig. 2 in full and broken lines, respectively.) 75

Upon the upper face of plate 11 is movably secured the guide clamp or plate 12 by means of screw 13, which passes through the guide clamp or plate 12 into plate 11. The plate 12 has upon its lower face two semi-cylindrical longitudinal grooves, 14, running parallel. Upon one side the plate 12 has an L-shaped arm, 15, the main and upright part of which is broad and flat, with a notch, 16, at its upper end. This arm 15 is placed with its flat face somewhat diagonal to the sides of the plate 12, which bears it, which is well shown in Fig. 4, and which is designed for a purpose herein-after described. The plate 12 can be easily turned about its pin 13 on the face of plate 11. 90

The friction-roll 17 is drum-shaped, and is covered with clothing 18, made of flannel or other similar suitable material. At the center of one end of roll 17 is fixed the screw-pin 19, which rests in notch 16 of arm 15, and is adapted to allow the roll 17 to rotate on its axis for new adjustment. 95

The thread-guide 20 consists of a doubled wire having the closed end formed into an approximate W form, the upper apex of which

is constructed with a loop-like guide-eye, 21, curved beyond said apex and having the ends or shoulders of the loop arranged one above the other, with a slight opening therebetween looking toward the bottom of the **W** form, said opening being intended for the admission of the thread into eye 21 when the thread is fed in between the outer apexes and toward the inner apex. Obviously this construction of guide-eye 21, with the diverging wires leading to the opening of the eye, admits of the thread 23 being fed therein by the thread being carried sidewise in toward the opening of the eye into the position shown in the figures. The guide-eye is thus self-feeding, since it is not required to thread the yarn or thread lengthwise through said eye; but it may be easily forced therein by a slight pressure sidewise. From the free ends of the **W** form extend rearwardly the parallel wires or strands, as shown. One of these parallel wires (shown in the drawings as the left-hand one) extends rearwardly a little longer than the other, which remains straight, and this longer wire is bent at right angles on itself and formed into the guide-eye 22. This thread-guide 20 is placed upon the upper face of the lower plate, 11, and clamped thereon by the upper plate, 12, so that the parallel wires take into grooves 14 upon plate 12, and can be reciprocated longitudinally therein. By means of screw 13 the guide can be clamped fast when adjusted, as desired. Obviously, by loosening the screw 13, by which the guide clamp or plate 12 is swiveled to the tilting plate 11, said guide-clamp 12 may be readily swung on the swivel in a plane cutting the axial line of the bobbin spindle or support 30 or 40, and the clamped thread-guide carried by said clamp may thereby have its guide-eye 21 adjusted laterally over the nose of the bobbin or cop 8 anywhere in an arc of which the swivel-screw 13 is the center. The thread 23, wound upon bobbin 8, runs from thence through guide-eye 21 over the friction-roll 17 down through guide-eye 22 onto the spool. (Not shown.)

The friction-roll 17 is, by means of the construction of its supporting-arm 15, adjusted to have its longitudinal axis placed otherwise than normal to a line at right angles to the axial line of the bobbin-spindle or inclined to the vertical plane containing the standard 7 and the axial line of the bobbin-spindle or support, and thereby allowing the track of the thread 23 over the roll 17 to be diagonal to said axis, so that by slightly rotating the roll upon its pin 19 the thread will find an entirely different track. This adjustment of the roll causes the clothing of the same to last much longer than ordinarily and saves time in the frequent replacement of the worn clothing which is usually required.

By my construction of the clamp 11 12, the thread-guide is adjustable therein longitudinally by virtue of the wires sliding in the grooves 14 and laterally in an arc whose center is the screw 13 by virtue of the said screw.

The longitudinal adjustment of the thread-guide is the adjustment of the thread-guide on its line of length and in a plane cutting the line of the thread carried by the guide. The lateral adjustment is the adjustment of the guide to either side of the said line of length and in the said plane. This thread-guide 20, because of these adjustments, can be readily and accurately adjusted to have its guide-eye 21 brought directly over the end of the bobbin and centered very close down upon the same, thereby preventing any damage to the thread by its beating and chafing about the head of the bobbin. These adjustments of my device reduce the ballooning to the minimum.

The clamp 11 12, rotating on its pivot 10 and carrying the thread-guide 20 and friction-roll 17, can be tilted back into the position shown by the broken lines in Fig. 2. When in this back position, the bobbin 8 can be readily withdrawn from its spindle and replaced by another when the clamp is tilted forward into normal position for operation.

In the modified form I show in Fig. 3 I have accomplished the same object as in the primary form. In said modification the plate 11 is made part of the standard 7 and is stationary. The tilting motion is now given to the spindle or skewer 30, which is hinged by its head 31, turning on pivot 32, fixed across the recess 33, made in the step 6. From recess 33 runs the cavity 34, extending back into the base of standard 7, where the flat spring 35 is secured in position by the screws 36. The free end of spring 35 projects across recess 33, and here the end of the head 31 of the spindle rests upon it to maintain the spindle in operative position. Upon the head 31 is a flat face running forwardly and upwardly, against which the spring 35 presses, when the spindle is drawn forward at the top, to allow the bobbin 8 to clear the thread-guide 20, which is here stationary, in the insertion and withdrawal of the bobbin. This motion of the tilting spindle and bobbin is an easy spring-acted motion, and any of the various constructions ordinarily employed upon the skewers of loom-shuttles may be adopted for use in this part of my device.

In Fig. 4 I have shown the spindle 40 as very short, to better enable the mounting and withdrawal of the bobbin. However, any well-known suitable means may be here used to maintain the bobbin in operative position.

It is obvious that by my constructions either of the tilting clamp and adjuncts, with spindle stationary, or by the tilting spindle and bobbin, with the clamp and adjuncts stationary, I secure a remarkably close centering adjustment of the delivering end of the bobbin and the eye of the thread-guide, thereby greatly reducing the harmful air-drag upon the thread.

In the operation of my device the ballooning of the thread never allows double ballooning or looping of the thread upon itself, which

is objectionable as damaging to the structure of the thread.

Practical use of my device shows that it admits of such high speed that the thread makes 5 double the number of circuits about the bobbin that the ordinary machines admit of, and that high speed does not lacerate or break the thread.

Obviously my device may be used with all 10 to its advantages in spinning all kinds of yarns. The yarn is composed of filaments arranged in regular systematic order, and if this order is preserved till the yarn is woven into fabrics these fabrics will be all the more perfect. My 15 device preserves this desired smoothness of structure of the thread and yet permits of running at a high speed.

There may be various modifications made 20 in all parts of my device without departing from the spirit of my invention as herein described and claimed.

I am aware of the heretofore construction 25 of means for adjusting a thread-guide in an arc lying in a vertical plane parallel to the axial line of the bobbin-spindle and also in a line normal to the said plane, and hence I disclaim such construction. I am not aware of the heretofore employment of means for the adjustment of a thread-guide longitudinally 30 in a line and laterally in an arc across the bobbin-nose; and, therefore,

Having thus described my invention, I claim 35 as new and desire to secure by Letters Patent—

1. The combination of an adjustable thread-guide with means, substantially as described, 40 for adjusting said guide longitudinally in a line and laterally in an arc, whereby the thread-guide I may be set and centered close to the delivery end or nose of a bobbin or cop and the moving thread may have the minimum of clearance between said guide-eye and bobbin-nose, for the purpose herein described.

2. The combination, with supporting means 45 and a swiveled guide-clamp mounted thereon, of a thread-guide placed in said guide-clamp and adjustable laterally in an arc and longitudinally in a line, substantially as and for the purpose herein described.

3. The combination of a bobbin spindle or 50 support and a thread-guide with a friction-roll having the axial line thereof set inclined or oblique to a line normal to the axial line of the bobbin-spindle or inclined to the vertical plane containing the standard and the axial line of said spindle or support, substantially as described, whereby the moving thread may find a diagonal path over the friction-roll, for the purpose set forth.

4. The combination of a bobbin spindle or 55 support and a thread-guide with a friction-roll turnable on its axis and provided with a support, the axial line of said roll disposed to inclined or oblique to a line normal to the axial line of the bobbin-spindle or inclined to a plane containing the longitudinal axis of said thread-guide and the axial line of said spindle or bobbin support, substantially as de-

scribed, whereby the friction-roll may be turned on its axis to shift the path of the thread moving thereon, for the purpose set forth.

5. The combination, with a standard or supporting means and a tilting plate or table swiveled thereon, of a guide-clamp swiveled on said plate or table, and a thread-guide 75 mounted in said guide-clamp and adjustable laterally in an arc and longitudinally in a line, substantially as herein described.

6. The combination, with supporting means and a guide-clamp swiveled thereon, of a 80 thread-guide mounted in said guide-clamp, and a supported friction-roll adjusted with the axis thereof inclined, substantially as herein described, whereby the thread may have a diagonal path over said roll, for the purpose 85 herein described.

7. The combination of a tilting plate or table swiveled in a vertical plane with a guide-clamp provided with guideways or grooves and swiveled upon said plate in a plane normal to 90 the plane said plate is swiveled in, a thread-guide sliding in the guideways of said clamp, an eccentric upright arm fixed upon said clamp, and a turnable friction-roll set on said arm, substantially as and for the purpose described. 95

8. The thread-guide consisting of a doubled wire formed at the closed end with a guide-eye re-entrant upon the thread-guide, said eye formed in the wire like a loop the ends or shoulders of which lie one above the other and 100 looking outwardly, whereby the thread may pass easily sidewise into the eye, substantially as described.

9. The thread-guide consisting of a doubled wire bent approximately W-shaped with the 105 free ends of the wire running parallel away from the top of the W, and having a guide-eye formed at the upper apex of said W, and constructed in a loop form, with the ends or shoulders thereof disposed one above the other 110 and the opening of the said loop form looking toward the bottom of the W, one of said free ends extended beyond the other and turned at right angles to itself to form a second guide-eye, substantially as and for the purpose described. 115

10. The combination of a tilting plate or table and a support or stand therefor, said table swiveled in a vertical plane upon the stand, with a guide-clamp provided with guideways and swiveled upon said plate in a plane at right angles to said vertical plane, an upright arm fixed eccentrically to said plate, a turnable friction-roll mounted on said arm and having the axial line disposed inclined or 120 obliquely to the axis of the swivel of said clamp, and a thread-guide placed in said guide-clamp and constructed, substantially as described, with a self-feeding guide-eye at one end and a guide-eye at the other end, said eyes 125 disposed one to each side of the axial line of the friction-roll, substantially as and for the purpose described.

11. The combination of the tilting plate or

table 11, swiveled or pivoted upon a support, and the guide-clamp 12, provided with guideways 14, and swiveled to the said plate, with the thread-guide placed in said clamp, substantially as and for the purpose described.

12. The combination of the tilting plate 11, swiveled on a support, and the guide-clamp 12, provided with guideways 14, and having the swivel-screw 13, with the thread-guide placed 10 in said guide clamp, the upright arm 15, fixed upon said guide-clamp, and the friction-roll 17, loosely mounted on said arm, substantially as described.

13. The combination of the standard 7, having a step 6, provided with a bobbin-support, and the tilting plate 11, swiveled upon the head of said standard, with the guide-clamp 12, provided with guideways 14, and swiveled upon

said plate by means of screw 13, the thread-guide placed in said clamp, the upright arm 20 15, provided with the notch 16, and the friction-roll 17, having the screw-bearing 19, substantially as and for the purpose described.

14. The thread-guide consisting of a doubled wire formed with the self-feeding guide-eye 21, substantially as described.

15. The thread-guide formed of the doubled wire 20, provided with the front guide-eye, 21, and the rear guide-eye, 22, substantially as and for the purpose described.

30 In witness whereof I have hereunto set my hand.

ARTHUR W. MATHEWSON.
